Inventor:

Emile Weil
Oscar M. Donaldson
Atty's.

UNITED STATES PATENT OFFICE.

EMILE WEIL, OF NEW ORLEANS, LOUISIANA.

MASONRY WALL AND INSERT THEREFOR.

1,331,834.

Specification of Letters Patent.

Patented Feb. 24, 1920.

Application filed April 4, 1919. Serial No. 287,529.

To all whom it may concern:

Be it known that I, EMILE WEIL, a citizen of the United States, residing at New Orleans, State of Louisiana, have invented certain new and useful Improvements in Masonry Walls and Inserts Therefor, of which the following is a specification.

My present invention relates to improvements in masonry and like walls and a damp proof insert for use in the mortar or plastic joint thereof and aims to provide an improved insert which may be readily applied to the joints in any desired lengths or in overlapping lengths to cover any desired number of bricks or blocks and prevent penetration of dampness through the wall.

The invention further aims to provide an insert which may be readily applied at any desired point, which will be efficient irrespective of any irregularities in the blocks of which the wall is composed, and which will not interfere with a bond surface for mortar or other binder efficiency.

The invention further aims to provide an insert which will adjust itself to joint thicknesses, and retard horizontal moisture penetration and also reduce absorption surfaces to a minimum.

With these and other objects in view the invention includes the novel construction and arrangement and combination of parts hereinafter described and particularly defined by the appended claim.

In the drawings:

Figures 1 and 2 are vertical transverse sections through walls having my inserts incorporated in the mortar joints thereof.

Figs. 3 to 11, inclusive, are detail cross sectional views of various forms of inserts.

Referring by reference characters to this drawing, the wall is shown as composed of blocks 1 which are intended to be representative of any suitable building blocks such as brick, stone or concrete. The mortar or other binder is indicated at 2.

My improved insert may be composed of felt, metal, or any composite water proof material either plain or reinforced of sufficient stiffness to maintain its form or outline and may be made in strips of any desired length.

My preferred form of strip is shown in Fig. 3 as having a portion 3^a adapted to lie upon the upper surface of a layer or course

of bricks or blocks and a vertical portion 3^b adapted to abut the vertical face of such course. The horizontal portion is provided with a longitudinal corrugation 3^c of a height corresponding approximately to the thickness of the mortar or other binder.

Instead of making the corrugation of inverted V-shape in cross section, as shown in Fig. 3, I may shape it by two right angular bends as shown in Fig. 4, providing a vertical portion 4^a of a height corresponding approximately to the mortar thickness, and a horizontal portion 4^b adapted to abut the under face of the next upper course of bricks or blocks.

In the form shown in Fig. 5 I form the corrugation by simply curving the upper edge upward as indicated at 5^a in Fig. 5, the curve being continued if desired to form a coil as shown.

For some joints I may omit the flat portion 3^a and simply provide a horizontal portion 6^b and corrugation 6^a as shown in Fig. 6 and if desired I may omit both vertical and horizontal flat portions and provide a plurality of longitudinal corrugations as indicated at 7^a, Fig. 7. One edge of the sheet or insert of Fig. 7 may be made to extend vertically downward to about the vertical face of the course of bricks as indicated at 8^a, Fig. 8, or may be carried horizontally beneath the corrugated portion as indicated at 9^a, Fig. 9.

In some instances I may use an insert of plain angular form in cross section, either of right angular form with the two portions 10^a and 10^b at right angles to each other, as shown in Fig. 10 or with one portion 10^a inclined at an obtuse angle to the other, as indicated at 11^a, Fig. 11.

Having thus described my invention, what I claim is:

In a plastic joint for masonry and the like, the combination with the upper and lower layers of bricks or blocks and the interposed plastic binder, of a layer of damp proof material embedded in said plastic binder, and having an off-set or corrugated portion corresponding to the thickness of the plastic material so as to contact with the surfaces of the adjacent bricks at top and bottom, said layer extending lengthwise for the full length of the joint.

In testimony whereof I affix my signature.

EMILE WEIL.
